JOHN J. GAYNOR, OF INDIANAPOLIS, INDIANA, ASSIGNOR TO PROGRESS MACHINE COMPANY, OF INDIANAPOLIS, INDIANA, A CORPORATION.

BOTTLE-CAPPING MACHINE.

1,155,908.

Specification of Letters Patent.

Patented Oct. 5, 1915.

Application filed July 20, 1914. Serial No. 851,965.

To all whom it may concern:

Be it known that I, JOHN J. GAYNOR, a citizen of the United States, and a resident of Indianapolis, county of Marion, and State 5 of Indiana, have invented a certain new and useful Bottle-Capping Machine; and I do hereby declare that the following is a full, clear, and exact description thereof, reference being had to the accompanying drawings, in which like letters refer to like parts.

The object of this invention is to improve the constructions of bottle capping machines, so as to reduce materially the compression required and, therefore, the breakage of bottles, and materially lessen the 15 power required to operate the machine and also to reduce the wear of the throat of the capping mechanism.

To those ends one feature of the invention 20 consists in employing a plunger which is actuated only by gravity normally and by a cam if the gravity fails to actuate the plunger sufficiently to dislodge the cap from the throat of the crowning head plate and providing means for limiting the movement of 25 such plunger in both directions, one of said means being adjustable.

The invention will be understood from the accompanying drawings and the following 30 description and claims.

In the drawings, Figure 1 is an elevation of a portion of the bottle capping machine, with parts in section and parts omitted. Fig. 2 is a section on the line 2—2 of Fig. 1, 35 but on a larger scale.

The drawings herein illustrate a type of bottle capping machine which is in practical use and has a base 10 and casing 11 with a driving shaft 12 and pinion 13 meshing with 40 a gear 14 for causing the rotation of an annular series of tubular bottle supports 15. Said bottle supports reciprocate their upper ends through a table 16 and centrally through said table a column 17 extends upward which carries the crowning head plates 18. Each of said plates 18 is integral with 45 a casing 19 extending upward therefrom and secured to the flanges 20 by bolts 21, and a collar 22 on the column 17 and just 50 below a hopper 23.

Each crowning plate 18 has a throat 24 to receive the upper end of a bottle 25. The upper portion of said throat is tapered up to an opening 26 through the top of said plate 55 so as to receive a cap 27. The caps are fed

from the hopper by means, not shown, through the opening 28 in the plate 18, indicated by dotted lines in Fig. 2. After the cap 27 has been fed into the throat 24 and upon the mouth of a bottle 25, said bottle is elevated by its bottle support 15 and the mouth of the bottle and the cap 27 are forced into the top of the throat 24 and thereby the crown forcibly secured on the mouth of the bottle. The construction and operation may be of any well known type.

In order to force downward and out of the throat the upper part of the bottle and the cap, a plunger 30 is mounted in the casing 19 with a reduced lower end extending into the opening 26 so as to engage the cap and the top of the bottle and force them downward. In fact, the lower end of the reduced portion of the plunger 30 forms the top of the throat 24 and serves as an abutment against which the cap and top of the bottle is forced upward by the bottle support. The plunger 30 is limited in its upward movement by a nut 32 which screws into the upper part of the casing 19 and it is held in place by a lock nut 33. Hence the nut 32 receives the strain of the upward thrust of the bottle support against the bottle and through it against the plunger 30. The limit of the upward movement of the 85 plunger being adjustable by the means explained, the device is readily arranged so as to operate properly for crowning bottles which may vary somewhat in size.

After the bottle has been capped, the cap 90 and bottle must be discharged and this is done normally by the gravity of the plunger 30 causing said plunger to descend until the shoulders 34 thereof engage the top of the plate 28 which limits the downward 95 movement of the plunger. If, however, the gravity of the plunger should not in a particular instance suffice to dislodge the cap and bottle, the plunger is forced downward by a cam 35 secured to the underside of a 100 rib 36 on the hopper 23, as seen in Fig. 1. The cam 35 engages the reduced upper end of the plunger 30 after the gravity of the plunger has had an opportunity to dislodge the cap.

With the foregoing construction, a bottle capping machine of this type can operate with very great rapidity as compared with previous bottle capping machines of this 110 or any other type and with the construction

of plunger mechanism for the dislodgment of the cap and bottle, as herein shown, the amount of pressure upon the bottle support and bottle is materially reduced and thus 5 the breaking of the bottles is overcome. In other words, with this machine, as compared with machines of the same type heretofore used, about three hundred pounds less pressure of the operating parts is required. This not only saves the bottles from 10 breakage, but reduces the power and expense of operation and enables the speed of the machine to be increased.

15 The bottle supports 15 are vertically movable by reason of being supported yieldingly by the spring 135 on the lower member 136 and because said lower member 136 revolves, due to the movement of the gear 14, whereby the rollers 37 on the lower end of each 20 member 136 rides upon the stationary cam plate 38.

The invention claimed is:

1. A bottle capping machine including a 25 capping plate with a tapering throat in it, a plunger for discharging the bottle and cap with its lower end projecting through the capping plate into the throat thereof, adjustable means for positively limiting the upward movement of the plunger at the instant that the throat of the capping plate 30 limits the upward movement of the cap and

mouth of the bottle, and a vertically movable bottle support.

2. A bottle capping machine including a 35 capping plate with a tapering throat in it to receive the cap and mouth of the bottle, a casing extending upward from said plate, a gravity actuated plunger in said casing, adjustable means secured to the upper end of the casing for positively limiting the upward movement of the plunger at the instant that the throat of the capping plate limits the upward movement of the cap and mouth of the bottle, and a vertically movable bottle support.

3. A bottle capping machine including a 40 capping plate with a throat, a casing extending upward from said plate, a gravity actuated plunger in said casing with the reduced end entering said throat and said plate limiting the downward movement of said plunger, a nut which screws into the upper end of said casing for positively limiting the upward movement of said plunger, and a vertically movable bottle support.

In witness whereof, I have hereunto affixed my signature in the presence of the witnesses herein named.

JOHN J. GAYNOR.
